UNITED STATES PATENT OFFICE.

RACHEL E. REZNICK, OF PHILADELPHIA, PENNSYLVANIA.

COMBINATION-GARMENT.

SPECIFICATION forming part of Letters Patent No. 742,904, dated November 3, 1903.

Application filed September 11, 1903. Serial No. 172,836. (No model.)

To all whom it may concern:

Be it known that I, RACHEL E. REZNICK, a subject of the Emperor of Russia, residing at Philadelphia, county of Philadelphia, and 5 State of Pennsylvania, have invented a new and useful Improvement in Combination Garments, of which the following is a full, clear, and exact description, reference being had to the accompanying drawings, which form 10 a part of this specification.

The object of my invention is to provide a combination garment to take the place of the usually separate waist or wrapper and corset and in such combination garment to substitute for the ordinary corset a bust-support that will be free from the objectionable binding and compressing features of a corset and that at the same time is so constructed as to adequately support the bust and impart to 15 the figure the graceful shape produced by a 20 stylish corset.

The invention consists of a waist or wrapper to the inside of which is secured, under the armpit on each side, one section of the 25 bust-support, each section being adapted to encircle the front half of the waist, the two sections overlapping and being secured together substantially under the armpits.

The invention also consists in so forming 30 each section that the end or half of the same adjacent to the secured end extends in front of the corresponding breast, while the other free end or half is more or less sharply cut away beyond the center, so as to pass under 35 the other breast, each breast being thereby given a double differential support that takes the place of the pocket of an ordinary corset.

The invention also consists in other details of shape and construction hereinafter fully 40 described.

I have shown my invention applied to a wrapper having an underlining, the front sections of which are free from the outer garment and provided with buttons and buttonholes, respectively, by means of which the front of the wrapper is fastened, although my invention is also applicable to a wrapper or waist in which the lining is secured to the outer garment throughout and in which the 45 50 fastening devices are placed on the outer garment.

In the drawings, Figure 1 is a front view of

the combination garment, showing the interlining and bust-support in their extended unfastened positions. Fig. 2 is a similar view 55 showing, however, the bust-support in its operative fastened position.

a is the outer garment. The back *z* of the lining is secured to the back of the garment in the ordinary way. The two front sections 60 *b* and *c* of the lining, however, are secured to the outer garment only along the neckband or collar, around the front half of the armhole, and underneath the center of the armhole. Buttons *x* extend along the front edge 65 of section *b*, and buttonholes *y* along the front edge of section *c*, by which means the wrapper is fastened in the front.

One section *d* of the bust-support is fastened to the lining underneath the armhole, 70 the line of fastening being substantially along the line of junction between the sections *b* and *c* of the lining and extending from a point *a* short distance below the armhole to about the waist-line. This bust-support section *d* extends entirely across the front of the garment 75 to a point substantially underneath the other armhole.

The bust-support section *d* is shaped substantially as follows: The top line of the same 80 is curved, sloping slightly upward near its secured end and extending substantially horizontal as it approaches the vertical center line of the garment. Beyond this point the top line drops sharply downward, thence 85 curves more gently downward, and thence substantially horizontally to the free end of the section. The bottom line of section *d* extends downward to the vertical center line 90 of the garment and thence extends upward 95 to the free end of the section.

The section *d* is composed of the vertical strips *h* and the stay-casings *i*, alternating therewith. There may be any suitable number of these strips and stay-casings, but preferably the end strips are substantially wider than the intermediate strips. Generally speaking, the strips extending across the wider half of the section and the strip or strips nearest the center along the narrower half of 100 the section are wider at the top and bottom than along their central portions in order to accommodate the same to the shape of the figure. For the same reason along the con-

tracted end portion of the narrower half of the section the strips are somewhat wider at the bottom than at the top. Stays *k* are inserted into the casings *i*.

5 The section *e* is in all respects a duplicate of section *d*, so far as the latter has been described, being secured, however, underneath the other armhole and extending entirely across the front of the garment to about the 10 line of fastening of section *d* and overlapping it or, as is shown in Fig. 2, being overlapped by section *d*.

The section *d* is provided, close to its line of fastening, with an eye *m*. A short distance 15 beyond its line of fastening it is provided with eyelets *o*.

The section *e* is provided, close to its free end, with a hook *n*, adapted to engage the eye *m*. A short distance from its free end it is 20 provided with hooks *p*, adapted to engage the eyelets *o*.

The section *d* is provided, close to its free end, with a hook *r*. A short distance from its free end it is provided with eyelets *t*.

25 The section *e* is provided, close to its line of fastening, with an eye *s*, adapted to be engaged by the hook *r*. A short distance beyond its line of fastening it is provided with hooks *u*, adapted to engage the eyelets *t*.

30 By the foregoing means the two overlapping sections of the bust-support are secured together at the sides, thereby supporting the breasts more comfortably, as well as more effectively, than in an ordinary corset, where 35 the two sections do not overlap and are secured together at the front.

Along the vertical center line of the front of the bust-support, or thereabout, a double stay—that is, one stay in each section—takes 40 the place of the steel strip in an ordinary corset, the latter being objectionable in that it is uncomfortable and apt to break.

The bust is well supported by reason of the fact that each breast is supported by the two 45 sections, one of which is full and the other of which is cut away.

The two-part bust-support of my combination garment is simple in construction and can be made quickly and inexpensively, it is 50 free from steels, buttons, lacing, and rubber, it can be washed and ironed, it can be readily clasped and unclasped, and it may be readily attached to or detached from any outer garment.

55 Having now fully described my invention, what I claim, and desire to protect by Letters Patent, is—

1. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, fastening devices secured near the

fastened and free ends of one section and complementary fastening devices secured near the fastened and free ends of the other section, whereby the two sections are secured together at the sides of the garment, substantially as described.

2. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 75 fastening devices whereby the sections are fastened substantially at the sides of the garment, substantially as described.

3. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 80 fastening devices whereby the sections are fastened substantially at the sides of the garment, substantially as described.

4. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 85 fastening devices whereby the sections are fastened substantially underneath the armhole, substantially as described.

5. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 90 fastening devices whereby the sections are fastened substantially underneath the armhole, substantially as described.

6. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 95 fastening devices whereby the sections are fastened substantially underneath the armhole, substantially as described.

7. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 100 fastening devices whereby the sections are fastened substantially underneath the armhole, substantially as described.

8. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 105 fastening devices whereby the sections are fastened substantially underneath the armhole, substantially as described.

9. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 110 fastening devices whereby the sections are fastened substantially underneath the armhole, substantially as described.

10. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 115 fastening devices whereby the sections are fastened substantially underneath the armhole, substantially as described.

11. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 120 fastening devices whereby the sections are fastened substantially underneath the armhole, substantially as described.

12. As a new article of manufacture, a combination garment consisting of the garment proper and a bust-support, the latter being composed of two sections, the sections being secured to the garment on opposite sides thereof, each section extending from one side around the front portion of the garment to the other side, the two sections thereby overlapping, 125 fastening devices whereby the sections are fastened substantially underneath the armhole, substantially as described.

bination garment consisting of the garment proper and a bust-support, the latter being composed of two sections, the sections being secured to the garment on opposite sides thereof, each section extending from one side around the front portion of the garment to the other side, the two sections thereby overlapping, each section being composed of alternating strips of fabric and stay-casings, stays in said casings, and fastening devices at the ends of the sections, substantially as described.

7. As a new article of manufacture, a combination garment consisting of the garment proper and a bust-support, the latter being composed of two sections, each section being composed of strips of fabric alternating with narrower stay-casings, stays in said casings, each section being secured to the garment substantially underneath one armhole and extending around the front of the garment to a point substantially underneath the other armhole, the two sections thereby overlap-

ping, the top line of each section extending slightly upward toward the central portion, 25 dropping sharply downward beyond its central portion and thence extending across to its free end, the bottom line of each section extending downward from its secured end to about its center and thence upward to its free 30 end, fastening devices secured near the fastened and free ends of one section, and complementary fastening devices secured near the fastened and free ends of the other section, whereby the two sections are secured together underneath the armholes of the outer garment, substantially as described.

In testimony of which invention I have hereunto set my hand, at Philadelphia, on this 27th day of August, 1903.
